CONVERSION OF HEAVY HYDROCARBONACEOUS MATERIALS

Richard W. Sage, Fanwood, N. J., assignor to Esso Research and Engineering Company, a corporation of Delaware

Application July 31, 1951, Serial No. 239,497

2 Claims. (Cl. 196—50)

The present invention relates to a method of treating hydrocarbons. More specifically, the invention pertains to an improved process of reducing the viscosity of heavy hydrocarbonaceous residues of the type of topped or reduced crude, asphalt, pitch, or similar materials by a thermal treatment suitable to produce motor fuel range hydrocarbons, gas oils and fuel oils of improved quality. In its broadest aspect, the invention provides for subjecting heavy residues of the type specified to a deoxygenation treatment followed by a viscosity-reducing or "visbreaking" treatment at high temperatures and elevated pressures to produce gasoline, gas oils and low sediment fuel oil.

In refining crude oil the first step is normally a simple distillation or "topping" to produce distillate fractions and a heavy residue. In order to obtain maximum yields of high quality motor fuels and middle distillate fractions suitable as heating oils, the crude oil fractions boiling above about 650°F. must be broken down into lower molecular weight compounds boiling in the range of 0°F. to 650°F. It is very desirable economically to produce from the material boiling higher than heating oil a maximum amount of heavy gas oil by distillation, light hydrocarbon precipitation, etc., this gas oil being processed by either thermal or catalytic cracking to achieve the maximum yields of high value motor fuels and heating oils discussed above. The residue (reduced crude) from the preparation of the heavy gas oil is disposed of as heavy (residual) fuel oil, usually after fluxing with a less viscous oil to a more usable viscosity. In order to obtain a maximum of high value products from the heavy residue and to minimize the amount of heavy fuel produced (and also to minimize the amount of flux oil required for viscosity reduction) the residue itself is also subjected to a thermal cracking operation as described below.

The thermal cracking of reduced crudes is known as visbreaking and yields gasoline, heating oil and gas oil as well as a reduced amount of residual material for a given viscosity. Visbreaking involves a treatment of reduced crude or the like at temperatures of about 780—950°F. and pressures of about 100—1500 p. s. i. g. at feed rates of 2—75 volumes per hour of oil at 60°F. per cracking volume above 750°F. to produce by a mild type of thermal cracking about 5—40 vol. per cent of gas oil, about 5—25 vol. per cent of gasoline and about 85—60 vol. per cent of heavy fuel oil. Specific conditions within the ranges specified depend on the type and boiling range of the visbreaker feed. The gas oil so formed represents a feed stock suitable for the production of additional amounts of high quality gasoline by catalytic cracking or, after suitable finishing, an acceptable distillate fuel. Of the products formed in visbreaking, the gasoline and gas oil have the highest and the fuel oil the lowest values.

Quite generally, therefore, it is desirable in visbreaking to reduce fuel oil yields in favor of higher yields of gasoline and gas oils. However, procedures suitable for this purpose, for example operating at an increased thermal cracking severity, affect detrimentally the quality

2

of the fuel oil. It is particularly difficult to produce a fuel oil of satisfactory sedimentation characteristics along with maximum yields of gasoline and gas oils. Any process by which the quality of the fuel oil portion of the visbreaker product may be improved while increasing the yields of other products is, therefore, of greatest interest. The present invention provides a process of this type.

It is, therefore, the principal object of the invention to provide means for producing a fuel oil of improved quality by visbreaking heavy hydrocarbonaceous residues. Other objects and advantages will appear from the subsequent description of the invention wherein reference will be made to the accompanying drawing, the single figure of which is a semi-diagrammatical illustration of a system suitable to carry out a preferred embodiment of the invention.

In accordance with the present invention, visbreaker feed stocks such as reduced crude or similar residues of the type specified above are subjected to a deoxygenation treatment immediately prior to being passed to the visbreaker unit. The deoxygenation treatment should be carried out in such a manner as to permit the substantially complete removal of the free oxygen contained in the visbreaker feed. Stripping of the feed with steam or other gases such as nitrogen or inert gas consisting predominantly of nitrogen and/or carbon dioxide at elevated temperatures of about 220° to 750°F. and atmospheric or slightly elevated pressures is suitable for this purpose. Lower pressures than atmospheric may be employed, if desired.

It has been found that the sediment-forming tendencies and asphaltene content of visbreaker tars increase appreciably upon contact of these tars with free oxygen. The experiments reported below bear out this fact.

A reduced crude (I. B. P. 1050°F.) was visbroken at about 930°F. and 350 p. s. i. g. for about 4 minutes above 750°F. The product was flashed to atmospheric pressure and heavy tar (about 600°F. I. B. P.) was separated from the gasoline and gas oils. The tar was fluxed with gas oil to a Saybolt Furol viscosity of 175 seconds at 122°F. The blend was then tested for sediment and asphaltene content prior to and after treatment with oxygen.

Sediment was determined by filtration after fluxing, sediment being reported as weight per cent of fluxed tar. Fuel oil blends having a sediment in excess of 0.3 wt. per cent are considered unsatisfactory. Asphaltenes were determined by precipitation with a light petroleum naphtha and measured as weight per cent of insoluble matter. The oxygen treatment consisted in bubbling oxygen through the blend for one hour at 212°F. The results of these tests are summarized below.

Condition of Fluxed Tar	Sediment, Wt. Percent	Asphaltene, Wt. Percent
Prior to O ₂ -Treatment	.26	12.8
After O ₂ -Treatment	1.8	14.5

It will be noted that both sediment and asphaltene content were materially increased by the oxygen treatment. Increases of this order seriously limit the value of the tar for fuel oil purposes since sediment and asphaltene content determine the quality of the tar as the residual component of a blended bunker fuel. Similar tests on the visbreaker feed from which the above visbreaker tar was produced have shown no significant changes in either sediment or asphaltene contents upon treatment with oxygen. These tests prove the particular sensitivity of visbreaker tar to the influence of free oxygen.

Visbreaker feed stocks like all other petroleum products contain free oxygen picked up in varying amounts from the air particularly during storage for an appreciable length of time. This oxygen causes, in the course of the visbreaking treatment, the formation of sediment and asphaltenes in the manner demonstrated by the above experiments. The severe conditions of temperature and pressure employed in the visbreaking operation, combined with the fine and uniform distribution of the oxygen in the feed strongly favor these undesirable side reactions.

The present invention eliminates these side reactions by removing the oxygen from the visbreaker feed. In this manner, the severity of the visbreaking treatment may be substantially increased so as to increase the yields of gasoline and gas oils without the simultaneous deterioration in the quality of the fuel oil product which has been previously experienced. The beneficial effects of the invention may be further enhanced by excluding air or free oxygen from visbreaker tar particularly at temperatures substantially above 100° F.

Having set forth its objects and general nature, the invention will be best understood from the more detailed description hereinafter read with reference to the drawing. The system illustrated in the drawing essentially comprises a deoxygenation tower 17, a visbreaking coil 35 and a separator tower 40. The functions and coaction of these elements will be presently described in connection with the treatment of a mixed feed of different refinery residues. It should be understood, however, that the system may be employed in an analogous manner for the visbreaking of other hydrocarbonaceous residues.

In operation, refinery residues from various sources may be fed to the visbreaking unit. For example, a residue from the atmospheric distillation of crude oil may be withdrawn from tankage and supplied via line 1. This material which may have a boiling range of about 500 to 1500° F. or higher may amount to about 5 to 50% of the total feed. Its oxygen content may be relatively high, amounting to, say, about 0.05 to 0.5 standard volumes of gaseous oxygen per liquid volume of residue chiefly as a result of long time storage. If desired, this portion of the feed may be preheated in a suitable heat exchanger 3 to about 500 to 700° F.

A second feed portion may be supplied through line 5 in the form of vacuum still bottoms. This material which boils above about 1050° F. usually has a relatively low oxygen content and may make up about 30 to 80% of the total feed. It is preferably supplied at the temperature of the vacuum still of, say, about 600-800° F. The remainder of the feed may be visbreaker products, extraneous gas oils etc., supplied to the system via line 7 at about 400-600° F.

The combined feed which may have a temperature of about 550-700° F. is passed through line 9 preferably to the convection section of coil furnace 11 to be heated in coil 13 to temperatures up to 800° F. The preheated feed is then further treated as follows.

Coil 13 discharges into line 15 which leads to the top of deoxygenation tower 17. The feed enters tower 17 through suitable distributing means such as spray nozzles 19, preferably at atmospheric or slightly elevated pressure of, say, 0-30 p. s. i. g. and predominantly in the liquid state. The temperature is maintained within the range of about 220° to 750° F. Tower 17 may be a bubble plate, disc-and-doughnut, or packed tower of a design conventional in the art of distillation and countercurrent liquid-gas contacting. A tower provided with disc-and-doughnut baffles 21 is shown in the drawing.

Steam preheated to about 500-800° F. is injected from line 23 through nozzles 25 into the bottom of tower 17. About 0.5-2.0 lbs. of steam per gallon of oil

feed is normally sufficient for the purposes of the invention. Free oxygen is stripped off the oil feed by the countercurrently flowing steam. A mixture of steam and oxygen is withdrawn overhead from tower 17 to be vented or passed via line 27 to a condenser for recovery of any minor amounts of heating oil and lighter products distilled off during stripping. Substantially complete deoxygenation of all practical visbreaker feed stocks may be accomplished within stripping times of about 10 to 10 60 seconds at the conditions specified.

When other stripping media such as nitrogen or mixtures of nitrogen and carbon dioxide are used in place of steam, stripping rates may be slightly lower and longer times required. The stripping agent should be completely devoid of free oxygen.

The oil feed now substantially free of oxygen, is withdrawn from tower 17 through line 29 and passed by means of pump 31 to preheating coil 33 and visbreaker coil 35 arranged, respectively, in the convection and radiant sections of furnace 11. The oil may enter coil section 33 at a temperature of about 650-750° F. and a pressure of about 100-1500 p. s. i. g., preferably about 300 to 400 p. s. i. g. The temperature of the oil in section 33 may reach about 700-850° F. Heating is continued in section 15 35 to a temperature of, say, about 850-950° F. Coil dimensions and oil feed rates are preferably so correlated that the oil residence time at visbreaking temperatures exceeding 750° F. will be about 0.8-30 minutes, corresponding to an oil throughput of about 75-2 volumes 20 of liquid oil per volume of visbreaking coil per hour (v./v./hr.).

The visbroken product is withdrawn at visbreaking pressure and a temperature of about 850-950° F. in mixed vapor-liquid phase via line 37. The product is flashed by 25 means of pressure release valve 39 into a lower portion of the baffled section of a separator tower 40 at a temperature of about 800-900° F. and a pressure of about 20-100 p. s. i. g. Stripping steam may be admitted to the tower 40 via line 42 at a point below the feed point 30 of line 37 to aid in the removal of distillate products including gasoline and gas oil which leave tower 40 overhead through line 44 to be further worked up in conventional fractionation and treating equipment, not shown.

Heavy visbreaker tar of a boiling range suitable for 35 inclusion in heavy fuel oil is collected in tar pot 46 and may be handled therein as follows. Product tar may be withdrawn via line 48 and passed to storage at a rate controlled by valve 50 operated by conventional level control means 52, such as a conventional ball float or differential pressure controller. The tar level in tar pot 46 is preferably so adjusted that a substantially constant tar hold up and a relatively short tar residence time are provided at the residuum feed rates here specified.

The system of the drawing permits of various modifications. If desired, the tar pot may be maintained at a 40 desirably low temperature of about 400-650° F. by continuously circulating tar from the tar pot through a cooler and back to the tar pot. Another stream of relatively cool product tar may be returned to line 37 to quench 45 the visbreaker product to any desired temperature between about 450° and 800° F. Other modifications will appear to those skilled in the art.

The above description and exemplary operations have 50 served to illustrate specific embodiments of the invention. It will be understood that the invention embraces such other variations and modifications as come within the spirit and scope thereof.

What is claimed is:

1. The process of converting heavy hydrocarbon oils into distillate oils and tar, which comprises distilling from said oils the constituents boiling below 650° F. to produce residual oils, stripping said residual oils so produced in a stripping zone with steam at a temperature of about 220° to 750° F. with about 0.5-2.0 lbs. of steam per gallon 55 of residual oil so as to remove free oxygen substantially

completely from said residual oils, recovering overhead from said stripping zone steam, oxygen and a minor amount of oils distilled during the stripping, immediately thereafter subjecting said oxygen-free residual oils to a vis-breaking treatment at relatively severe conditions including temperatures of about 850° to 950° F., pressures of about 300-400 p. s. i. g. and oil throughputs of about 2-75 v./v./hr. adapted to produce a vis-broken material relatively rich in distillate fractions, and flash-separating said material at a substantially lower pressure into distillate fractions and heavy tar suitable as a residual fuel oil.

2. A method of inhibiting sedimentation and asphaltene formation during vis-breaking of heavy hydrocarbonaceous residues containing free oxygen which comprises completely deoxygenating said residues by steam stripping in a deoxygenation zone using steam in an amount in the range of 0.5 to 2.0 lbs. per gallon of said residues for a time in the range of 10 to 60 seconds, recovering

overhead from said deoxygenation zone steam, oxygen and minor amounts of oils distilled during the stripping, and immediately thereafter vis-breaking the deoxygenated oils at higher than normal severities including a temperature in the range of 850° to 950° F. and a feed rate in the range of 2 to 75 v./v./hr. whereby increased yields of distillate fractions are obtained while obtaining a residual fuel oil of satisfactory sedimentation characteristics.
